UNITED STATES PATENT OFFICE.

EMILE GÉRARD, OF LIMOGES, FRANCE, ASSIGNOR TO OLIVER A. GAGER, OF BROOKLYN, NEW YORK.

DESIGN FOR THE ORNAMENTATION OF DISHES.

SPECIFICATION forming part of Design No. 19,066, dated April 30, 1889.

Application filed April 20, 1887. Serial No. 235,564. Term of patent 7 years.

To all whom it may concern:

Be it known that I, EMILE GÉRARD, a citizen of the French Republic, residing in Limoges, France, have invented or produced a new and original Design for a Set of Dishes, of which the following is a specification.

This design relates to a set of dishes comprising plates, platters, saucers, fruit-dishes, gravy-dishes, and various other dishes, 10 whether deep or shallow.

The design pertains to the surface ornamentation of the dishes.

In the accompanying photographs, Figure 1 is a plan view of a platter. Fig. 2 is a perspective view of a gravy-boat, looking from the side. Fig. 3 is a plan of the saucer or plate on which the gravy-boat shown in Fig. 2 is set. Fig. 4 is a plan view of a platter or other shallow dish, and Fig. 5 is a plan view 20 of a plate.

I will first describe my design as illustrated in Fig. 1. The dish or platter here shown is elongated, with substantially straight sides and rounded ends, the ends being contracted 25 or indented at *a a* near their junction with the straight sides. The depressed center *A* of the dish is devoid of ornamentation, and has straight side outlines, *b b*, which at the ends are curved inward at *c c*, forming a re- 30 entering angle with the end outline, *d d*. The latter are substantially elliptical, curving inward shortly at *e e*, where they join the curved portions *c c* of the side outlines. The rim *B* of the dish extends around the center *A* par- 35 allel with the outline thereof, being varied by a raised rib, *f*, extending inward from each indentation *a a*. The opposite ends of the dish are varied by ornamental handles *C C*, appearing on the rim *B* and seeming to 40 project beyond the same. There is an ornamental border, *D*, upon the rim *B*. This border consists of a succession of radial figures, *g g*, in low relief, appearing like bars or pickets pointed at the outer ends and grooved or 45 scooped out longitudinally in their middles, as clearly shown in the photographs. A rib or stripe, *E*, extends around the rim *B* close to the outline of the depressed center *A* of the dish, and the border *D* is disposed next out- 50 side of this stripe and appearing to spring from beneath it. The stripe *E* consists of

two ribs, *h h*, with an intervening row of dots, *i*. Along the outer portion of the rim is a border, *F*, which consists of a row of convex scallops, and in each scallop a conventionalized flower showing three petals, as best seen at the ends of the dish in Fig. 1. Between the flowers are small acorn-shaped figures simulating seeds or seed-pods. The stripe *E* and border designs *D* and *F* cover the entire width of the rim and extend entirely around the same except in four places, where they are interrupted—namely, at the two opposite ends of the dish, where they are interrupted by the handles *C C*, and at the middle of the straight sides of the dish, where they are interrupted by a circular design, *G*. The circular designs *G G* consist each of a complete circular figure, *m*, the outline of which comes to the extreme edge of the rim 70 of the dish, and of a concentric outer portion, *n*, which constitutes little more than half of a complete circle, being interrupted at the edge of the rim, where it terminates in straight lines *j j*. This ornament *G* is clearly 75 shown in Fig. 2, where it is applied to a dish of different shape. In either case the circular center *m*, projecting beyond the general outline of the edge of the dish, gives to the latter a convex curve, *p*, in the arc of a circle, and on each side of this curve *p* are the straight lines *j j*, which join it nearly in the general outline of the edge of the dish and extend from it at such an angle that their outer ends project beyond the general out- 80 line, thereby forming steps or shoulders *q q*, which extend thence inward to the straight outline, as shown. The circular figure *m* is ornamented by a conventionalized flower in its center and by an annular border sur- 85 rounding this flower and consisting of two concentric circles with an intervening row of dots. The outer concentric figure, *n*, is ornamented by a series of figures, *r r*, which may be described as ovals drawn to a point at 90 at their smaller ends and arranged closely side by side with their pointed ends directed inward toward the center. These figures *r r* are designed to simulate seeds or seed-pods. Outside of this row of pointed figures is a 95 semicircular border-line, which bounds or incloses the design *G*, and the ends of which

extend to and coincide with the steps or shoulders *q q* in the outline of the edge of the dish. The handles *C C* are ornamented by a fan-shaped figure, *s*, which is a conventionalized flower springing or radiating from a stem, *t*, and the outer radial lines curving outwardly, as shown. The stem *t* appears to pass beneath a cross-bar, and from beneath the latter appear two small scroll-like knobs, 10 *o o*. On the opposite side of the cross-bar the stem *t* and the stems from these two scrolls appear to radiate, and from them spring two small leaves, *u u*, which extend in opposite directions upon the rim and adjacent to the 15 figure *s*. The outer part of the figure *s* projects beyond the general outline of the edge of the dish, imparting to the outline a convex extension at each end of the dish. The remainder of the handle design is entirely 20 within the rim. The handle designs *C C* and the side ornaments, *G G*, are in somewhat greater relief than the remainder of the ornamentation, so that the border designs upon the rim of the dish, where interrupted by 25 them, appear to pass beneath them.

Figs. 2 and 3 illustrate, respectively, a gravy-boat or similar deep dish and its saucer or stand. The latter dish differs considerably in its shape from that shown in Fig. 1, in that 30 its sides are not straight, but are curved in the arcs of circles or ellipses, while its ends are considerably more convex. The indentations *a a* and radial ribs *f f* are retained, crossing the ornamented rim of the dish in the 35 same manner and imparting to it in some respects much the same appearance. The general shape of the dish is elliptical, varied by the indentations *a a* at four nearly equidistant points. The depressed center *A* is of 40 the same shape, having curved side outlines, *b b*, and end outlines, *d d*. The rim *B* is ornamented by the stripe *E* and the borders *D* and *F*, as before, the only difference being that, in consequence of the altered shape of 45 the dish, the radial figures *g g* radiate more uniformly and from more nearly a common center. The border or stripe *E*, instead of bounding the depressed center *A*, is disposed somewhat apart from the outline *d d* thereof, 50 leaving a plain intervening space, *e'*. The side ornaments, *G G*, in Fig. 1 are omitted from this dish; but it has the handles *C C* at its ends. These handles consist each of the 55 radial conventionalized floral figure *s*, with its stem *t*, the other parts of the handle design being omitted in order to conform to the narrow proportions of the end portions of the dish.

The gravy-boat or deep dish shown in Fig. 60 2 has in plan the same outline as the dish shown in Fig. 3. Its vertical outlines are clearly shown in Fig. 2. Its opposite sides are swelled outwardly, the creases *f f* being approximately parallel or concentric with the 65 outline of the figure *G* on the side seen in Fig. 2. The upper outline of this side is broken by the curved line *p*, the straight lines *j j*, and

the offsets *q q*, pertaining to the ornamental figure *G*. The opposite side of the dish is varied by the handle *C*, which projects farther 70 beyond the general outline of the edge than in the other dishes. The handle *C* is here of the same design as in Fig. 1, with the exception that the leaves *u u* extend farther to each side and terminate at the outline of the dish, 75 instead of being merely ornaments applied on the surface of the rim inside of the edge thereof, as before. The ends *H H* of the dish are swelled outwardly beneath substantially parallel with the creases *f f*, and their upper portions are curved outwardly, passing into lips or spouts, the upper side outlines, *d' d'*, being curved upwardly, as usual. With the exception of the handle design *C*, all the ornamentation is on the exterior instead of the interior of 80 the dish. Around the bottom of the dish extends a border design identical with the borders *D* and *F* in Fig. 1. Around the top of the dish and parallel with its edge extends a border figure, *I*, consisting of a row of approximately 85 heart-shaped outlines or links, *a'*, parallel with and close to the edge of the dish, then a border, *b'*, consisting of two lines and an intervening row of dots, (identical with the stripe *E* in Fig. 1,) then a row of oblique 90 heart-like figures, *c'*, and finally a row of vertical pendants or tassel-like figures, *d'*. This ornamental border *I* is interrupted by and appears to pass beneath the ornamental figure *G*. 100

The dish shown in Fig. 4 is of approximately the same shape in plan as that shown in Fig. 3, being an ellipse varied by indentations *a a*, with creases *f f* extending thence across the rim. This dish is considerably 105 deeper than that shown in Fig. 3. The depressed center *A*, instead of being plain, as in the other dishes shown, is ornamented with a design, *J*, which consists of a stripe, *f'*, of elliptical form, varied by four indentations in 110 consonance with the outline of the dish, enclosing a central rosette or conventionalized flower and a series of radial figures, *g'*, and outside of which stripe is a series of radially-arranged seed-shaped figures, *h'*, or ovals drawn 115 to a point with their apexes turned toward the stripe. The general outline of this design *J* is approximately parallel with the outline of the depressed center of the dish. The rim *B* of this dish is ornamented by the 120 border designs *D* and *F*, which extend around it close to its inner outline, and with a border design, *I*, which extends around it close to its outer outline. Between the designs *F* and *I* is a plain space. The design *I* consists of 125 the ornamental rows or stripes *c'* and *d'*, (shown in Fig. 2,) the stripe *b'* there shown being omitted in order to make the design narrower. The handles *C C* are formed almost entirely on the rim of the dish, the floral figure *s* 130 having but a slight projection beyond the general outline of the end of the dish. Each handle design consists of the conventional radiating floral figure *s* and its stem *t*, with the

scroll-like ornaments *o o*. The stem *t* extends down upon the depressed center *A* of the dish and is expanded thereon.

Fig. 5 shows a round plate. The circular outline of the plate is varied by indentations *a a*, as in the other figures, from which indentations radial ribs *f f* extend across the rim, thereby dividing the latter into six (more or less) lobes or sectors. The outline of the depressed center *A* of the dish is also varied by indentations or by the continuation into its margin of the ribs *f f*, as shown. The rim *B* is ornamented with the stripe *E* and the border designs *D* and *F*, as in Fig. 1.

What I claim, and desire to secure by Letters Patent, is—

The design for a set of dishes having the surface ornamentation as shown in the accompanying photographs and as described.

In witness whereof I have hereunto signed my name in the presence of two subscribing witnesses.

EMILE GÉRARD.
